[57] CLAIM

The ornamental design for a fluid delivery set, as shown and described.

DESCRIPTION

FIG. 1 is a perspective view of a fluid delivery set showing our new design;

FIG. 2 is a front elevation view thereof;

FIG. 3 is a top view thereof;

FIG. 4 is a left side elevation view thereof;

FIG. 5 is a right side elevation view thereof;

FIG. 6 is a rear elevation view thereof; and,

FIG. 7 is a bottom view thereof.

It is understood that the broken-away portion of the tubing represents an indeterminate length.
